(No Model.)

C. M. STOLLE.

AMALGAMATOR.

No. 369,135.

Patented Aug. 30, 1887.

UNITED STATES PATENT OFFICE.

CARL M. STOLLE, OF BELLEVUE, IDAHO TERRITORY.

AMALGAMATOR.

SPECIFICATION forming part of Letters Patent No. 369,135, dated August 30, 1887.

Application filed March 4, 1887. Serial No. 229,699. (No model.)

To all whom it may concern:

Be it known that I, CARL M. STOLLE, of Bellevue, in the county of Alturas and Territory of Idaho, have invented a new and Improved Amalgamator, of which the following is a full, clear, and exact description.

The object of my invention is to provide a new and improved amalgamator which is simple and durable in construction and very effective in operation.

The invention consists in the construction and arrangement of various parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a perspective view of my improvement with one of the amalgamating-plates removed from the top cylinder. Fig. 2 is a vertical cross-section of part of the cylinder, showing the fastening of one of the amalgamating-plates. Fig. 3 is a similar view of the same, showing the construction of the frame supporting the said plates; and Fig. 4 is a similar view of the same, showing the frame and the said plates.

On suitably-constructed standards, A and A', is mounted the hollow shaft B, provided with the perforations B', and supporting the amalgamating-cylinder C, which is smaller in diameter at one end than at the other, and in this smaller end opens the sluice or chute D. The other larger end of the cylinder C opens into the casing E, supported by the standard A, and provided with the downwardly-extending chute E', the lower bent end of which opens into the second amalgamating-cylinder, F, supported on the shaft G, mounted in the standards A and A' and provided with the pulley H, connected by the belt I with the pulley J, secured on the shaft B, which is also provided with the usual fast and loose pulleys for revolving the said shaft. One end of the cylinder F, into which opens the said chute E', is slightly smaller in diameter than its other end, which opens into the casing K, having the downwardly-extending chute K', which opens upon the tailings-box L.

The cylinders C and F are preferably hex-

agonal in cross-section, and as they are alike in construction it suffices to describe one. On the shafts B and G, respectively between the standards A and A' and suitable distances apart, are placed the hubs N, on which are secured the spokes O, on the outer ends of which are secured, by means of angle-irons and bolts or rivets, the wooden frames P, provided with external grooves, P', in which are placed the copper plates Q, amalgamated on their inner faces, and held in place on the said frames P by latches R, which permit of removing the plates for cleaning or other purposes. The spokes at the small ends of the cylinders C and F are inclined inward, so as to permit of extending the ends of the respective chutes D and E' into the respective cylinder C or F.

To one outer end of the shaft B is coupled the water-supply pipe S, provided with a valve or cock, T, for regulating the passage of the water through the perforations B' in the shaft B into the interior of the cylinder C.

The operation is as follows: The cylinders C and F are set in motion simultaneously, and then the pulp or gold-sand is introduced into the cylinder F at its small end by the chute D. The rotation of the cylinder F agitates the pulp or sand and causes the heavier particles of gold to separate from the pulp, the said particles being thrown by centrifugal force against the amalgamated surfaces of the copper plates Q, which thus retain the gold firmly. The pulp passes toward the larger end of the cylinder C, and is finally discharged into the casing E, which delivers it to the second cylinder, F, in which the above-described operation is repeated, and all the remaining particles of gold are absorbed by the amalgamated plates Q before reaching the larger end of the cylinder F. The tailings are discharged from this larger end of the cylinder F into the tailings-box L. In case the pulp entering by the chute D is thick, then the operator opens the valve T and admits water through the perforations B' into the cylinder C, thus thinning the pulp. The valve is also opened to admit water into the cylinder F when the supply of pulp ceases and the operator desires to clean the cylinders C and F. The water then washes the remaining pulp out of the cylinders, the rotation of which is now stopped, and the amalgamated plates Q are removed and treated in the usual man-

ner to obtain the gold. The last set of amalgamated plates Q, near the casing E in the cylinder C, are amalgamated only throughout one-half their length, so as to catch all the amalgam which may become loosened from the preceding plates.

For certain kinds of pulp it is only necessary to run it through the upper cylinder, C, and in this case I may entirely dispense with the lower cylinder, F, and its connections.

To further define my invention and distinguish it from others in the same general class, I will state that the tapering shape of the so-called "cylinders" facilitates the passage of the tailings from one end to the other, and that their polygonal form causes the tailings to be thrown from one plane surface or plate onto another with a force which promotes separation of the gold and its adherence to the said plates.

Having thus fully described my invention, I claim as new and desire to secure by Letters Patent—

1. In an amalgamator, the combination, with a shaft, a cylinder supported on the said shaft, said cylinder being of polygonal shape, tapering from one end to the other, and provided with removable amalgamating-plates, of a casing, into which opens the large end of the said cylinder, a chute extending downward from the said casing, and a second amalgamating-cylinder of polygonal shape tapering from one end to the other, and into the smaller end of which opens the said chute, substantially as shown and described.

2. In an amalgamator, a hollow perforated

shaft, a cylinder supported on the said shaft and being polygonal in shape, tapering from one end to the other, and provided with removable amalgamating-plates, in combination with a casing, into which opens the larger end of the said cylinder, a chute extending from the said casing, a second amalgamating-cylinder of polygonal shape, tapering from one end to the other, and provided with straight removable amalgamating-plates, and a shaft supporting the said cylinder and operated from the perforated shaft by suitable means, substantially as shown and described.

3. In an amalgamator, a hollow perforated shaft, a water-supply pipe connected with the said shaft, a cylinder supported on the said shaft and being of polygonal shape, tapering from one open end to the other, and provided with straight removable amalgamating-plates, in combination with a casing, into which opens the large end of the said cylinder, a chute extending downward from the said casing, a second amalgamating-cylinder of polygonal shape, tapering from one open end to the other, and provided with straight removable amalgamating-plates, a shaft supporting the said cylinder, means, as described, for revolving the said shaft from the said hollow shaft, and a casing having a chute, and into which opens the large end of the said second amalgamating-cylinder, substantially as shown and described.

CARL M. STOLLE.
